UNITED STATES PATENT OFFICE.

ELLWOOD T. KNIGHT, OF PHILADELPHIA, PENNSYLVANIA, ASSIGNOR TO HOHLFELD MANUFACTURING COMPANY, A CORPORATION OF PENNSYLVANIA.

JACQUARD MECHANISM FOR LOOMS.

Application filed July 14, 1921. Serial No. 484,563.

To all whom it may concern:

Be it known that I, ELLWOOD T. KNIGHT, a citizen of the United States, and a resident of the city of Philadelphia, in the 5 county of Philadelphia, State of Pennsylvania, have invented certain new and useful Improvements in Jacquard Mechanism for Looms, of which the following is a specification, reference being had to the accompanying drawing.

This invention relates to jacquard mechanism for looms and it consists of certain improvements therein as hereinafter set forth and illustrated in the drawings forming a part hereof.

The invention aims to provide a novel and advantageous mechanism adapted to be operated when desired to turn the pattern card cylinder backward, and, at the same time, 20 to automatically throw out of action the devices for turning the cylinder forward to permit the backward turning thereof.

In the accompanying drawings, illustrating the invention:

25 Figure 1 is a side view of sufficient of a jacquard machine to illustrate my invention.

Figure 2 is a transverse section through the pattern card cylinder, showing the needle receiving openings therein.

30 Figure 3 is a sectional detail showing the devices for turning the pattern card cylinder.

Referring to the drawings, 2 designates the frame of the machine and 3 the horizontal needles supported and guided in parts carried thereby and adapted to be actuated by the pattern cards for the selection of the vertical wires which are operatively connected to the warp threads to be 35 raised and lowered by the jacquard machine, in accordance with the pattern dictated by the cards, in the usual well known manner.

The pattern card cylinder 4 is journaled in suitable bearings in the side members 45 5 of a reciprocative frame 6 comprising the members 5, arms or brackets 7 secured thereto and extending outwardly and downwardly therefrom, a bar or shaft 8 connecting the lower ends of the arms or brackets 7, and horizontal, parallel shafts 9 extending from the members 5 and slidably fitted to bearings 10 on the frame 2 of the machine.

Each shaft 9 has a bracket 11 secured 55 thereto and provided with a cam slot 12

therein, and, extending into the cam slot 12 in each bracket 11 is a pin 13 projecting from a collar 14 fixed on a rod or shaft 15 which is fitted to slide vertically in bearings 16 on the frame 2, and which carries 60 the usual lifter frame of the machine, whereby, when the rods 15 are raised and lowered by the usual, well known, mechanism to raise and lower the lifter frame, the frame 6 carrying the cylinder 4 will be 65 reciprocated horizontally.

The chain of pattern cards 17 passes around the cylinder 4 each end of which is provided with the usual ratchet member 18 adapted to be engaged by the tooth 19 of 70 a pawl arm 20 to turn the cylinder 4 a quarter revolution and present a fresh card 17 to the needles 3 each time the cylinder 4 is moved toward and from the needles. The pawl arm 20 is pivoted, at 21, to the frame 75 2 and it rests normally upon one of the ratchet members 18. At the conclusion of each movement of the cylinder 4 it is retained in position, with the card 17 thereon facing the needles 3 in vertical position, by 80 the horizontal bottom surface of stop pawls 22 engaging the two top teeth of the ratchet members 18. The stop pawls 22 are fitted to slide vertically in the brackets 5, and they are passed normally toward the ratchet 85 members 18 by springs 23; and, when the cylinder 4 is turned, the teeth of the ratchet members 18 raise the pawls 22 against the action of the springs 23.

The card cylinder 4, near the respective 90 ends thereof, is provided with teeth 24 which enter holes 25 in the end portions of the cards 17 and cause them to turn with the cylinder and to register with the flat surfaces thereof.

95 Adjacent to one of the ratchet members 18 is a pawl arm 36 having a projecting tooth 37 adapted to engage the ratchet member to turn the card cylinder backward. The pawl arm 36 is carried by one arm 38 100 of a lever 39 which is fulcrumed, at 40, on the reciprocative frame 6, and which is provided with a tooth 37 adapted to engage the ratchet. The upper end of the arm 36 is pivoted to the lever 39, and the lower end 105 of the arm 36 is connected by a spring 41 to a projection 42 on one of the arms or brackets 7 of the frame 6. The spring 41 draws the pawl arm 36 into engagement with the ratchet member 18, and, when the 110

arm 43 of the lever 39 is lowered and raised, the pawl arm 36 will be reciprocated to cause its tooth 37 to engage the teeth of the ratchet member 18 and turn the card cylinder 4 5 backward and thereby reverse the direction of movement of the chain of cards 17, when it is desired to move it backward for any purpose.

The lever arm 43 is provided with a 10 pending rod 44 which extends to a convenient position to be operated by hand to raise and lower the lever arm 43 to move the chain of cards backward.

The pawl arm 36 is arranged laterally 15 adjacent to the pawl arm 20 and it is provided with a projection 45 which extends beneath the pawl arm 20 and is adapted to engage the same and raise or throw it out of operative relation to the teeth of the 20 ratchet member 18 to permit the cylinder 4 to be turned backward when the lever 39 is operated to raise and lower the pawl arm 36 for that purpose.

It will be understood that variations and 25 changes in the details of construction, arrangement and location of parts would readily suggest themselves to persons skilled in the art and fall within the spirit and scope of my invention. I do not desire, 30 therefore, to be limited or restricted to the exact details of construction and arrangement shown and described.

Having thus described my invention, I 35 claim and desire to protect by Letters Patent of the United States:

1. In a jacquard mechanism and in combination, a frame, a reciprocative frame thereon, means to reciprocate the latter, a pattern card cylinder carried by the reciprocative 40 frame and provided with a ratchet member for turning the same, means to turn the cyl-

inder forward when its carrying frame is reciprocated, means carried by the reciprocative frame to turn the cylinder backward, and means to automatically throw the 45 second named means out of action when the third named means is operated.

2. In a jacquard mechanism and in combination, a frame, a reciprocative frame thereon, means to reciprocate the latter, a pattern card cylinder carried by the reciprocative frame and provided with a ratchet member for turning the same, a pawl carried by the frame and adapted to engage said member to turn the cylinder forward when its carrying frame is reciprocated, and a pawl device carried by the reciprocative frame and adapted to engage said member to turn the cylinder backward, said device being provided with means to move said pawl out of 55 operative position.

3. In a jacquard mechanism and in combination, a frame, a reciprocative frame thereon, means to reciprocate the latter, a pattern card cylinder carried by the reciprocative 65 frame and provided with a ratchet member for turning the same, a pawl carried by the frame and adapted to engage said member to turn the cylinder forward when its carrying frame is reciprocated, a pawl to engage 70 said member and turn the cylinder backward, a lever fulcrumed on the reciprocative frame and connected to the last named pawl to actuate the same, and a projection on the second named pawl to engage the first 75 named pawl and move it out of operative position when said lever is operated to actuate the second named pawl.

In witness whereof I have hereunto set my hand this 13th day of July, 1921.

ELLWOOD T. KNIGHT.
